ELECTRICAL DROP-CORD FIXTURE

Lee H. Peck, Chagrin Falls, Ohio, assignor to
Porcelain Products, Inc., Findlay, Ohio, a corporation of Delaware

Application December 12, 1938, Serial No. 245,139

3 Claims. (Cl. 173—327)

This invention relates to improvements in electrical drop-cord fixtures.

An object of the present invention is to provide an improved drop-cord fixture comprising a minimum number of parts arranged for easy manufacture and assembly and one which is very simple to wire up in use.

Another object of the invention is to provide a drop-cord fixture formed almost entirely of dielectric material which is formed in such a manner as to require only two simple contact parts fitting into pockets in the dielectric to complete the device.

Other objects of the invention comprise the design and arrangement of the parts so as to carry out the purposes of this invention and will be more apparent from the specification and drawing and the essential features thereof will be summarized in the claims.

In the drawing, Fig. 1 is a top plan view of the base member of the device; Fig. 2 is a bottom plan view of the cover portion of the device; Fig. 3 is a top plan view of the cover member of Fig. 2; Fig. 4 is a central longitudinal section along lines 4—4 of Figs. 1 and 2 through the device with the cover and base members assembled; Fig. 5 is a portion of the bottom plan view of Fig. 2 with the electrical contact members removed; Fig. 6 is a sectional view taken along the line 6—6 of Fig. 5; while Figs. 7 and 8 are two views of a contact member.

Many of the inventive features of my device may be utilized in fixtures designed for different applications and the present embodiment shows one type which is useful for open wiring and to this end the device has been made long and narrow and preferably not over 1½ inches in width so as to fit over the edge of a 2 x 4 wooden structural member.

In Figs. 1 and 4 I have shown a base member 10 of a type adapted to be used with a plurality of different fixtures and it will be understood that the present invention may use this base member or any other suitable base member. In the form shown in Figs. 1 and 4 the base member comprises a single block of dielectric material such as porcelain. This block has a central raised portion 11 and depressed portions 12 at each end thereof, there being the usual knock-out portions 13 in the end walls of the base member or cover member, or partly in both as here shown to permit the introduction of the wires of an electric circuit. The central portion 11 has a plurality of parallel grooves 14 running lengthwise of the block in which are secured electrical conductors

15 which are permanently secured to the block as by the grommets 16. It will be understood that certain of the knock-out portions may provide openings through which electric wires are passed and secured by the screws provided to any of the conductors 15 in the base member. Openings 17 through the bottom wall of the base member are for attaching the same to a supporting structure.

The cover member 18 is preferably a single block of dielectric material such as porcelain generally hollow in form having side walls 18a, end walls 18b and a bottom wall 18c. It will be noted that the side and end walls end in a common plane and are adapted to engage similar walls 15 on the base member so that when the two are assembled as shown in Fig. 4 the parts inside are completely enclosed in dielectric material thus giving a very safe device. A raised portion 19 on the base member engages in a notch 20 in one of the side walls of the cover member so as to insure the assembling of the parts in a predetermined relation.

Portions 21 of dielectric material are arranged to receive the contact members for conducting electricity to the drop-cord. Preferably as in the form shown these are reinforcing or partition walls extending between the side walls 18a of the cover member and integral therewith. It will be noted that there is an opening 22 provided centrally of the bottom wall 18c to permit the entrance of a drop-cord inside the cover member. The reinforcing walls 21 are spaced one on either side of this central opening. As most clearly shown in Figs. 5 and 6 there is a pocket 23 in each of the walls 21 which is narrow and generally rectangular in form so as to admit a metal plate contact member with a slight amount of clearance. Two metal contact members are required and I have made them exactly alike for ease in manufacture although it will be understood that they need not necessarily be alike. As shown in Figs. 7 and 8 each contact member 24 has a flat attaching portion 24a into which is threaded a screw 25 by which an electric wire 45 may be secured thereto. Extending away from the attaching portion at an angle thereto and from one side thereof is a contact portion 24b. These contact members may be of resilient copper.

In assembling the parts the attaching portion 24a of each contact member is inserted in one of the pockets 23 and means is provided for insuring the proper assembly of the parts. To this end a slot 26 on one side of the pocket 23 is made

too small to pass the head of the screw 25, while a slot 27 communicating with the pocket on the opposite side is sufficiently wide to pass the head of the screw. When the parts are assembled in the proper manner as shown in Fig. 2 one of the contact portions 24b will overlie the central conductor 15 in the base and the other contact portion will overlie the right-hand conductor 15 as viewed in Fig. 1. It will be understood that the cover member of Fig. 2 is turned over on top of the base member of Fig. 1 in the assembly operation. The assembled parts are shown in Fig. 4 and are held assembled by bolts 28 which pass through suitable openings in the cover member and enter threaded grommets in the base member. When the parts are so assembled the base member and electrical conductors thereof press against the resilient contact portions 24b pressing the contact members into the bottom of the pockets 23.

It will be seen that I have provided a device having a few number of parts and simple to manufacture and that everything is so arranged that it cannot possibly be assembled in the wrong manner.

What I claim is:

1. A drop-cord fixture comprising a block of dielectric material having a central hollow portion, there being an opening through the lower face of said block to admit an electrical conducting cord, there being two pockets in said block, one on each side of said hollow portion, said pockets being narrow so as to admit a metal plate with slight clearance, metal plate contact members, one for each pocket, each member having a

flat attaching portion adapted to fit in one of said pockets and an integral contact portion outside of said pocket, a screw threaded into each attaching portion for securing an electrical conductor thereto, there being a slot adapted to pass the head of said screw communicating with each pocket on one side thereof only whereby each contact member must be assembled in its pocket in a predetermined manner, a base member secured to said block, and electrical conductors on said base member positioned to engage said contact portions when said base is attached to said block. 5

2. A drop-cord fixture as in claim 1, wherein said contact members are identical, each having its contact portion extending at an angle from its attaching portion, said contact members and pockets being arranged to space said contact portions transversely of said block, and coacting means on said block and base member insuring assembly so that said conductors engage said contact portions in a predetermined manner. 10

3. A drop-cord fixture as in claim 1, wherein said contact members are of resilient metal and identical, each having its contact portion extending at an angle from its attaching portion, said contact members and pockets being arranged to space said contact portions transversely of said block, coacting means on said block and base member insuring assembly so that said contact portions engage said conductors in a predetermined manner, and said base member pressing said contact members into the bottoms of said pockets. 25 30
